Inventor

S. W. Trabue

UNITED STATES PATENT OFFICE.

SARAH W. TRABUE, OF GIRARD, ILLINOIS.

BALING-PRESS.

SPECIFICATION forming part of Letters Patent No. 367,868, dated August 9, 1887.

Application filed June 13, 1887. Serial No. 241,204. (No model.)

To all whom it may concern:

Be it known that I, SARAH W. TRABUE, a citizen of the United States, residing at Girard, in the county of Macoupin and State of Illinois, have invented a new and useful Improvement in Baling-Presses, of which the following is a specification.

My invention relates to improvements in that class of baling-presses in which the plunger is operated by means of a lever or sweep having an enlargement at one end provided with a cam-shaped slot in which works a friction-roller journaled at the end of a pitman, the other end of which is pivotally connected to the plunger.

The invention consists in certain novel features, hereinafter first fully described, and then pointed out in the claims.

In the accompanying drawings, which fully illustrate my invention, Figure 1 is a plan view of my improved baling-press. Fig. 2 is a central vertical longitudinal section of the same, and Fig. 3 is a detail view of one of the spring-buffers.

Referring to the drawings by letter, A designates the press-box, constructed in the usual manner and of the usual or any preferred size.

B designates the plunger working in the press-box, and provided on its outer side with the integral lugs or projections C, which are provided with vertical perforations, through which a pivot-pin, D, is inserted to secure the end of the pitman E to the plunger.

At one end of the press-box I secure upon the upper and lower sides of the same the cross-bars a a, in which the king-bolt F is journaled. This king-bolt F has an angular base, G, or lower end, which is provided with the depending cylindrical projection g, stepped in the lower cross-bar, while the upper portion is cylindrical and extends up through and above the upper cross-bar. The operating lever or sweep H is secured to the lower angular portion, G, of the king-bolt, and its inner end is formed with an angular notch, so as to readily engage and fit around said angular portion of the king-bolt. In order to maintain the sweep in a true horizontal position, I provide the brace or connecting-rod I, one end of which is secured to the upper end of the king-bolt, and the other end of which is se-

cured to the sweep at a proper point of its length.

The operating-cam or lever-head J is secured to the inner end of the lever or sweep H, and is also supported by and secured to the upper end of the angular portion of the king-bolt. By the employment of this construction I am enabled to obtain a positive and powerful pressure with a small expenditure of force, as the power applied to the sweep is not entirely consumed and applied directly to the cam-head J, but is partially applied to overcoming the inertia of the king-bolt and rotating the same, and the rotation of the king-bolt assists in giving motion to the cam-head. This cam-head is provided with a cam-shaped slot, K, in which works a friction-roller, L, carried by the end of the pitman E. This pitman E consists of two parallel arms, e e, connected at their inner ends by a cross-bar, e', from which the perforated offset e' projects rearwardly between the lugs C on the plunger, the pivot pin D being passed through the said offset to secure the pitman to the plunger. The outer ends of the arms e e pass above and below the cam-head J, and the roller L, working in the slot K, is journaled in and between the same.

M M designate two braces, which have their upper ends secured to the upper corners of the press on opposite sides of the king-bolt and extend therefrom to the ground at equal angles. Upon these braces M, I secure the spring-buffers N, which are arranged in the path of the sweep H to limit the play of the same, and thereby shorten the operation of baling by preventing the sweep being carried to either side farther than is necessary, and consequently saving the time otherwise lost in an useless expenditure of labor. The buffers consist of the strong coiled springs O, secured rigidly at one end to the braces M, and the plates P, secured to and carried by the free ends of the springs O.

The operation of my device will be readily understood. The hay or cotton to be baled is placed in the press-box in the usual manner, and a horse or other draft-animal hitched to the sweep and driven alternately to the opposite sides of the press. The cam-head is thus caused to force the plunger inward upon the hay, as will be readily understood, and each

turn of the sweep causes the cam-head to force the plunger inward and then withdraw it in position to permit the insertion of an additional quantity of material.

5 It is thought the advantages of my improved press will be readily appreciated without being particularly referred to in detail.

Having thus described my invention, what I claim, and desire to secure by Letters Patent, 10 is—

1. The combination of the sweep H with the rigid braces M, and the spring-buffers secured to the braces in the path of the sweep, substantially as set forth.

15 2. The combination of the sweep H with the rigid braces M, and the spring-buffers secured to the braces in the path of the sweep, the said buffers comprising the springs O, secured to the braces, and the plates P, secured to the 20 springs O, substantially as specified.

3. The combination of the press-box having the cross-bars a a at one end, with the plunger working in the press-box, the king-bolt

having the angular portion G, provided with the cylindrical projection g, stepped in the 25 lower cross-bar, a, and the cylindrical portion extending up through and above the upper cross-bar, the sweep having a notched end to engage the said angular portion of the king-bolt, the connecting-rod having one end secured to the upper end of the king-bolt and its other end secured to the sweep, the cam-head secured to the end of the sweep, and also secured to and supported by the angular portion of the king-bolt and provided with a cam-shaped slot, and the pitman connected to the plunger and carrying a friction-roller working in said cam-shaped slot, substantially as 30 specified.

In testimony that I claim the foregoing as 40 my own I have hereto affixed my signature in presence of two witnesses.

SARAH W. TRABUE.
